HENRY KAILIMAI, OF DETROIT, MICHIGAN

STEEL FOR STRINGED MUSICAL INSTRUMENTS

Application filed December 8, 1930. Serial No. 500,836.

This invention relates to tone-regulating steels for stringed instruments.

In present practice, such steels must be gripped between the thumb and fingers, and their manipulation to establish selective string-damping positions involves a flexing and torsion of the wrist muscles which, if at all protracted, imposes considerable fatigue.

An object of the present invention is to adapt a steel to be so attached to the hand of a musician as to relieve the hand of supporting effect, and leave the thumb free to effect a rapid angular shifting of the steel, eliminating the wrist movement heretofore required.

Another object is to provide a resilient finger piece serving to permit a steel to be quickly attached to and detached from a musician's hand, and to impose a torsional force upon the steel tending to yieldably establish it in a normal preferred angular relation to the strings of a guitar or like instrument.

These and various other objects the invention attains by the construction hereinafter described, and illustrated in the accompanying drawings, wherein:

Fig. 1 is a perspective view of a guitar, showing the herein-disclosed steel engaging the strings thereof in a transverse relation thereto.

Fig. 2 is another perspective view of the same, showing the steel engaging the strings, in a diagonal relation thereto.

Fig. 3 is a similar view showing a position of the steel reversely diagonal to that shown in Fig. 2.

Fig. 4 is an enlarged perspective view of the steel and its resilient finger piece, indicating how the latter may engage a musician's hand.

Fig. 5 is an end view of the invention, indicating in dash lines an engaged guitar string.

In these views, the reference character 1 designates an ordinary guitar, having the usual strings 2 and fretted neck 3, along which said strings extend.

In playing such an instrument, the strings are plucked by the right hand, centrally of 50 the sound box, and are stopped with the left

hand at selective points on said neck. To conveniently stop all or a portion of the strings, a bar of steel (or other suitable material) may be held in the left hand and pressed against the desired strings. 55

The present invention comprises a steel bar 4, and a coiled wire finger-piece 5 for securing said bar to the index finger of the musician. The damper bar is preferably of steel and cylindrical in form, although not necessarily of that particular metal or form. The finger piece 5 consists preferably of a short length of spring wire, forming convolutions spaced and proportioned to form a finger-receiving socket. Said finger piece 65 engages the steel eccentrically of its length, and preferably about half-way between its front end and center. The axis of the finger-engaging coils extends preferably clear of the bar, adjacent to one side of the latter, 70 and preferably inclines slightly toward the central transverse plane of the bar, in extending from the latter.

Closely adjacent to the bar the finger-piece comprises one or more convolutions 6, the 75 axis of which is substantially radial to the bar.

Connection of the finger piece to the bar is established in any suitable manner, as for example, by inserting an end portion of the 80 spring wire in a saw slot in the bar and closing said slot, by an upsetting of its edges firmly on the wire.

In use of the described device, the index finger of the musician's left hand is initially 85 so inserted into the spaced coils of the finger piece that the middle phalanx of the finger is gripped by said coils.

When so inserted, the terminal phalanx of the finger lies adjacent to and at one side 90 of the forward end of the bar. The finger is now turned to terminally rest on the forward end of the bar, the rear end of the bar being at the same time restrained by the thumb. There results a slight tensioning 95 of the convolution 6 tending to swing the bar to the position shown in Fig. 2. The bar is now applied to the strings, or any thereof, and its angular relation to the strings is controlled with negligible effort by regula- 100

tion of the restraint imposed by the thumb on the rear end of the bar. A moderate restraint maintains the bar transverse to the strings as shown in Fig. 1. A slight increase 5 of restraint establishes the diagonal position of Fig. 3 and a relief of restraint permits the bar to assume the reverse diagonal position of Fig. 2.

It is to be understood that the bar in swinging 10 between its limiting diagonal positions pivots about the axis of the convolutions 6 and that said convolutions are variably tor- sioned in selecting desired inclinations of the bar to the plane of the strings. It may also 15 be noted that the bar can be conveniently established at an inclination to the plane of the strings to facilitate its engagement with the latter individually or with several adjacent strings independently of the remainder.

20 Thus, the described bar affords a complete stopping control of the strings, and in accom- plishing this result imposes a minimum of physical effort upon the controlling hand.

Both the bar and its finger piece are in- 25 expensive, as is likewise their assembly op- eration, and the resiliency of the finger piece coils readily adapts them to fingers varying considerably in size.

Several important advantages accrue from 30 the cylindrical form of the bar, additional to the possibility of cutting it inexpensively from a readily available standard steel prod- uct. The described bar has the same line contact with the strings regardless of its 35 angular position with regard to its longitudi- nal axis. This is not true of any bar with a flat working face such as have heretofore been used. Furthermore, the line contact per- mits the bar to be slipped along or across 40 the strings or swung at an angle to the strings with a minimum of friction and ef- fort.

While it is apparent that the illustrated 45 embodiment of my invention is well calcu- lated to adequately fulfill the objects and advantages primarily stated, it is to be under- stood that the invention is susceptible to variation, modification and change within the 50 spirit and scope of the subjoined claims.

50 What I claim is:

1. A steel for stringed musical instruments comprising a damper bar, and a finger piece comprising coaxial metallic coils for engage- 55 ment by a finger establishing an axis clearing the bar and comprising a convolution closely adjacent to the bar and having its axis sub- stantially radial to the bar.

2. A steel for stringed musical instruments comprising a substantially cylindrical metal- 60 lic bar and a socket-forming finger piece se- cured to said bar between the ends thereof.

65 3. A steel for stringed musical instruments comprising a metallic bar and a wire finger piece rigidly terminally attached to said bar between the ends of the bar, said finger piece

being coiled adjacent to said bar about an axis approximately transverse to the longitudinal axis of the bar, and further integrally comprising a portion coiled about an axis acutely divergent to the axis of the first 70 named coil.

4. A steel for stringed musical instruments comprising a string-engaging bar, a member forming a finger socket, and means securing 75 said socket to the bar in an acutely angular relation to the length of the bar, said means affording the bar a travel relative to said socket about an axis approximately trans- verse to the bar.

In testimony whereof I sign this specifica- 80 tion.

HENRY KAILIMAI.
